his Attorney.

UNITED STATES PATENT OFFICE.

LLOYD BROWN, OF LOS ANGELES, CALIFORNIA, ASSIGNOR TO SILENT DRAMA SYNDICATE, A TRUSTEESHIP, LLOYD BROWN AND ALEXANDER GRAYDON, TRUSTEES.

DESIGN FOR A SUPPORTING-FRAME FOR MOTION-PICTURE MACHINES.

55,977.

Specification for Design.

Patented Aug. 10, 1920.

Application filed December 19, 1919. Serial No. 346,189. Term of patent 14 years.

To all whom it may concern:

Be it known that I, LLOYD BROWN, a citizen of the United States, residing at Los Angeles, in the county of Los Angeles, State of California, have invented a new, original, and ornamental Design for a Supporting-Frame for Motion-Picture Machines, of which the following is a specification, reference being had to the accompanying drawing, forming part thereof.

The figure is a perspective view of a supporting frame for motion picture machines, showing my new design.

I claim:

The ornamental design for a supporting frame for motion picture machines, as shown.

LLOYD BROWN.
